Wiley, both of Marion, Ind.

Application May 27, 1942, Serial No. 444,672

7 Claims. (Cl. 18—45)

This invention relates to a male plunger die structure capable of changing shape under pressure and when confined by a complementary female die.

This application is a continuation-in-part of application Serial No. 288,343, filed August 4, 1939, now Patent No. 2,337,581, entitled Sheet pulp container forming process and apparatus therefor, and more particularly Figs. 16 to 19, inclusive, thereof, and application Serial No. 316,742 filed February 1, 1940, entitled Sheet pulp container forming process and apparatus therefor, and more particularly Figs. 1 and 2 thereof.

The former application refers to and discloses a solid metal male die of non-expanding type (Fig. 16) and a metallic, mechanically expanding male die (Figs. 17 to 19). The latter application refers to and discloses a solid rubber male die deformable under pressure.

In all punches or male dies, not ported for pressure or vacuum application, the present invention is applicable.

It has been long known that paper material is somewhat abrasive in character when there is relative movement between the material and a working member engaging same.

In the former application, the plunger or male parts are exposed to the presence of moisture, size, synthetic and natural resins, et cetera, and the latter enter between the relatively movable parts of the die and tend to rust and clog same, respectively.

In the latter application, the rubber plunger or male die to have the necessary rigidly includes hardening and/or toughening agents, such as lamp black and the like. This plunger working on clear pulp sheets discolors, by sluffing rubber particles and coloring materials, the resulting container, which when finished are usually ivory-like in appearance, unless the pulp impregnating materials utilized are controlled to produce a substantially transparent product.

Since these containers usually are utilized in lieu of china (cups) and glass jars (cans) et cetera, wherein clean and sanitary appearance is highly desirable, it is important that any discoloration be prevented.

Lubricant between relatively movable parts of the mechanically expandable plunger or male die, also if it escapes externally will discolor the product.

The chief object of the present invention, therefore, is to provide means to not only protect the die against wear, clogging et cetera but more

particularly to protect the ware against discoloration.

The chief feature of the present invention consists in providing plungers or male dies of the aforesaid types with very thin latex coverings of about the same thickness, elasticity and consistency of toy balloons. Such sheaths are similar to the die in the non-expanded form and are smaller than the same so that they require stretching for die mounting and accordingly are held upon the die by their own tension and will not be stripped from the die in the normal use thereof. This sheath preferably is substantially colorless and of approximately pure latex.

Other objects and features of the invention will be set forth more fully hereinafter.

The full nature of the invention will be understood from the accompanying drawings and the following description and claims.

In the drawings

Fig. 1 is a central sectional view through an apparatus for blanking, preliminarily creasing and then fitting a precreased blank into a receiving female mold with the male die therein and under initial pressure and with a sheath interposed between the male die and the article being formed thereby.

Fig. 2 is a similar view of the female die, the article, the male die with the sheath thereon, the latter being shown in the fully expanded position.

Fig. 3 is a top plan view of one embodiment of a mechanically expansible die with the sheath applied thereto.

Fig. 4 is a similar view of the latter, half of the parts being shown in elevation and the other half being shown in central section, the section being taken on the line 4 of Fig. 3 and in the direction of the arrow.

Fig. 5 is a central sectional view of the invention shown in Figs. 3 and 4, the section being taken along the line 5 of Fig. 3 and in the direction of the arrow.

Fig. 6 is a perspective view of a sheath unapplied to the expansible male die.

Reference will first be had to Figs. 1 and 2, the so-called solid rubber die disclosure and initially to Fig. 1. In this figure there is provided two spaced supports 10 and 11 between which there is passed intermittently a flat pulp sheet A. Also positioned between these two supports and slidably supported by one support, herein 10, as at 12 and yieldingly constrained as at 13, is a stripper plate 14. Adjacent thereto is a cutting die 15 rigid with one support and associated therewith

and in juxtaposition thereto is another and co-operating cutting die 16 rigid with support 11. Relative movement of one support toward the other accordingly insures shearing from the sheet A blank which is nested between the two shearing die members 15 and 16.

Within each of the die members is a cooperating creasing structure including the cooperating portions 17 and 18 which are movable towards and away from each other in the aforesaid relative movement of the spaced supports previously set forth. Accordingly, when the blank is formed by shearing, the same is creased and then a support 19, carrying the stem neck 20 and a male die head arrangement 21 of solid rubber type, advances through the apertures 11a, 16a and 17a to draw the blank through the tubular portion 22 of the creasing structure.

Continued travel of the die seats the pre-created, partially formed blank designated in Fig. 1 by the letter B in a receiver die 23, of female type. This die is supported upon a base 24 which is movable and the die is provided with a valve controlled vent arrangement 25 and 26 to permit the escape of air trapped in the die in the initial seating of the semi-formed article and the male punch, therein. Continued movement of the member 19, since the rubber die is deformable under greater pressure, will cause the rubber die to conform to the interior 23a of the female die, thus forcing the article B to conform thereto and at the same time to compress the preformed flutes in the article side wall and also to redistribute the stock, as illustrated more particularly in Fig. 2.

Herein the female die 23 includes a throat or open mouth 27 and the male portion includes an annular extension or sleeve 28 which adjacent the die head forms a chamber 29. When the throat portion 27 and the skirt portion 28 are suitably associated together, as shown in Fig. 2, and the member 19 is sufficiently advanced, the two telescope and accordingly confine the so-called solid plunger and cause the latter to fill the chamber 29 as illustrated in Fig. 2 and fully occupy the enclosed arrangement except for that portion occupied by the article B.

As previously pointed out, there are certain inherent disadvantages resulting from the use of the construction as thus briefly described.

Referring to Fig. 6 it will be observed that there is therein illustrated a sheath substantially cylindrical in form in its body portion, the same being indicated by the numeral 30. One end is closed as at 31. The other end is open and defined by a reenforced portion 32. This sheath is of substantially the same thickness and elasticity as toy balloon stock. It is, however, colorless, or substantially so. It is of substantially pure latex.

This sheath is applied to the solid rubber male die 21 and by reason of its elasticity it will stretch and conform to the same substantially throughout its entire area of contact with the die. These sheaths may have an initial conformation corresponding to the die outline et cetera. However, this is not necessary because of the inherent elasticity of the sheath material. When applied to the rubber die the sheath will closely conform to the surface of the die throughout all the sheath covered portions of that surface and this is by reason of the fact of the inherent elasticity before mentioned and the frictional contact between the sheath and the die.

It is observed that in Figs. 1 and 2 the die has a reentrant free end 21a. In mounting the sheath

in such an instance in view of the fact that the largest diameter of the die is intermediate the ends thereof, care must be exercised to exclude all air trapped between the sheath and the die end and this is effected as follows:

The sheath may be inverted so that its end portion 31 may be pressed against the reentrant portion and then it can be reinverted after all the air has been removed between the reentrant portion of the die and the sheath. This will cause the sheath to substantially conform to the die end. Then the rest of the sheath can be worked back toward the neck portion supporting the die proper and when the die is completely covered, the remainder of the sheath will engage upon the rear face of the die head portion, this rear face being indicated by 21b.

After proper mounting, the apparatus previously described, is manipulated in proper timed relation, as set forth in the application before mentioned, to form a blank, precrease it, seat it in the receiver mold, then collapse the flutings in the side walls and then redistribute the stock, by extension of the solid rubber die. During this operation, the sheath is interposed between the article and the die and accordingly, the die is not subjected to wear and neither will the die slough the rubber particles therefrom incident to such wear nor will any of the coloring matter or the other material in the die which might emanate therefrom be applied to the article, so that the article is clean and devoid of extraneous matter.

The elasticity is such, as previously set forth, that the sheath adheres to the male die so that when the male die is retracted from the receiver mold the sheath moves therewith, being in effect unitized therewith. Naturally when the movement is such that the male die is no longer expanding, there is no suction between the article-receiver die and the male die and accordingly, the sheath is not then subjected to suction tending to remove it from the male die.

In Figs. 3 to 5, inclusive, there is illustrated an embodiment of a solid metal, mechanically expansible male die structure. For convenience, the receiver mold and article are omitted therefrom. Herein the numeral 50 indicates a main support, 51 indicates a sleeve slidably thereon and within a collar portion 52, the two being aligned by means of a pin 53 carried by the portion 50 and seated in the aperture 54 in the collar 52. This pin between the main support portion 50 and the collar 52 rides in a slot 55 in the sleeve 51.

Secured to the sleeve 51 is a collar 56 which is suitably associated with mechanism for mechanically expanding the die, as hereinafter briefly pointed out.

It will be observed that the support for the die structure which is associated with the portion 50 is caused to move at appropriate times so that the member 50 is moved longitudinally into a receiver mold wherein there is positioned an article of the character previously described. When fully seated therein, the sleeve 51 is caused to advance in the same direction to mechanically expand the die to insure proper compression and formation of the article. Following such operation the sleeve is caused to return, which contracts the male die and then the male die is caused to return to its original position, permitting the female die with the article included therein and properly finished in accordance with male die application to be removed for article removal or further treatment.

The end of the member 60 is enlarged and extended laterally at the free end as at 60 and this is suitably tapered at its outer portion 61. The collar portion 62, before mentioned is integral with the portion 62 and the latter is secured to the portion 60 by the means indicated at 63, 64, 65, and the nut 66, there being three of these constructions.

It will be observed that this connection is of shouldered type so that there is provided between the upper edge 61a and the lower edge 62a or faces, a channel of predetermined height. The portion 60 is recessed as at 61. Portion 62 is recessed as at 68. A movable portion of the die 69 which has an exterior face 70 includes a portion 71 seatable in the recess 61 and the portion 72 seatable in the recess 68. Springs 73 and 74 respectively, urge this member 69 into the retracted position. The member 69 has the inner inclined face 75 and this is engageable by the wedge portion 76, an extension of the sleeve 51. When the wedge moves down—see Fig 4—the member 69 moves outwardly from the full line position shown in Fig. 4, to the dotted line position thereof.

There also is provided somewhat similar members 79 having the exposed face 80 somewhat similar to the exposed face 70. Herein the recess 67 is of annular character and the member 79 includes a depending portion 81. It is also seated in such recess. The member 79 has the inner inclined face 86 also engageable by the cam face 76 on the sleeve 51.

The member 79 includes a longitudinal bore 82 therethrough and through this bore extends the portion 64, previously set forth. The portion 64 in turn is recessed as at 84 and springs 85 are interposed between one wall of the bore 82 and the member 64 being seated in the recesses 84 thereof. Hence, the member 79 is normally constrained to retracted position. When the sleeve 51 is caused to advance toward the free end 60 the wedge cam face 76 engages the several faces 75 and 86 of the several expandable members and moves them outwardly to the dotted line positions to form a complete periphery of expanded type.

The sheath shown in Fig. 6 is mounted on this solid metal mechanically expandable male die and when the latter is in the collapsed or retracted position and when so mounted, the reenforced end 32 rests on the shoulder face 90 of the portion 62 as illustrated. This shoulder edge may be slightly rounded as indicated at 91 so that it will not have a sharp cutting edge and, therefore, will not cut the sheath. As previously described, such a sheath, by reason of its inherent elasticity and because it is initially slightly smaller than the male die when collapsed, will stretch and be frictionally engaged with the male die when collapsed and yet will expand as required, when the die is enlarged laterally. In operation the friction lock between the sheath and die is such that any suction action between the article and the male die following the dieing operation will not be sufficient to strip the sheath from the die. Any tendency along that line naturally is resisted by the shoulder or face association with the reenforced end 32 of the sheath.

This form of the invention it will be apparent, prevents resting and clogging of the die, because the moisture, size and resin materials, respectively, of the article then cannot obtain access to the male die pressure applying surfaces, et cetera, and furthermore, any lubrication included in this male die cannot accidentally escape and discolor the article. Furthermore, the sheath itself takes

any abrasive wear which the articles might have upon the die.

From the foregoing, therefore, it will be apparent that in both embodiments of the invention illustrated, the article is protected from the male die and the male die in turn is protected from the action of the article so that replacement of the sheaths as they wear, et cetera, will insure substantially permanency of the dies mentioned.

While the invention has been described in association with laterally expandable dies, it is apparent that a sheath of this character may be utilized to prevent wear of the male die when the same is of solid metal and non-expandable type, at least one of which is illustrated in one of the aforesaid copending applications.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a die structure comprising a substantially closed end female die adapted to receive a cup-like, pressure moldable product, and a male die supported at one end by a male die support and with the product between the dies, said male die comprising a body portion supported at one end by said support and the end opposite the supported end being free and of pressure molding type and laterally expandable incident to the application of axial pressure thereto after insertion into the female die, and a rubber-like sheath telescopically mounted upon the body portion and peripherally enveloping the same and the female die received free end of the male die, the internal peripheral dimensions of said sheath normally being slightly smaller than the external peripheral dimensions of the body portion when not expanded, said sheath having sufficient inherent elasticity for self-retention upon the male die body portion and for expanding therewith.
2. In a die structure comprising a substantially closed end female die adapted to receive a cup-like, pressure moldable product, and a male die supported at one end by a male die support and with the product between the dies, said male die comprising a body portion supported at one end by said support and the end opposite the supported end being free and of pressure molding type and laterally expandable incident to the application of axial pressure thereto after insertion into the female die, and a rubber-like sheath telescopically mounted upon the body portion and peripherally enveloping the same and the female die received free end of the male die, the internal peripheral dimensions of said sheath normally being slightly smaller than the external peripheral dimensions of the body portion when not expanded, said sheath having a sufficient inherent elasticity for self-retention upon the male die body portion and for expanding therewith, the male die support at its junction with the male die having a cross-sectional area appreciably less than that of the male die at that junction, whereby the male die at that junction forms a shoulder, said sheath having its open

end positioned upon said shoulder and defined by a slightly reenforced edge.

3. A die structure as defined by claim 1 wherein said expansible male die comprises relatively movable parts and is of mechanically expansible type, said sheath preventing clogging of the male die parts.

4. A die structure as defined by claim 1 wherein said expansible male die is of so-called solid rubber type, said sheath closely conforming to the surface thereof for the protection of the product in all stages of die expansion, said sheath being of a rubber-like material other than that of the so-called solid rubber type and which will not contaminate the interior surface of the pressure moldable product.

5. In a die structure comprising a substantially closed end female die adapted to receive a cup-like, pressure moldable product, and a male die supported at one end by a male die support and with the product between the dies, said male die comprising a body portion supported at one end by said support and the end opposite the supported end being free and of pressure molding type and laterally expansible incident to the application of axial pressure thereto after insertion into the female die, and a rubber-like sheath telescopically mounted upon the body portion and peripherally enveloping the same and the female die received free end of the male die, the internal peripheral dimensions of said sheath normally being slightly smaller than the external peripheral dimensions of the body portion when not expanded, said sheath having a sufficient inherent elasticity for self-retention upon the male die body portion and for expanding therewith, the male die support at its junction with the male die having a cross-sectional area appreciably less than that of the male die at that junction, whereby the male die at that junction forms a shoulder, said sheath having its open end positioned upon said shoulder and defined by a slightly reenforced edge, said expansible male die comprising relatively movable parts and being of mechanically expansible type, said sheath preventing clogging of the male die parts.

6. In a die structure comprising a substantially closed end female die adapted to receive a cup-

like, pressure moldable product, and a male die supported at one end by a male die support and with the product between the dies, said male die comprising a body portion supported at one end by said support and the end opposite the supported end being free and of pressure molding type and laterally expansible incident to the application of axial pressure thereto after insertion into the female die, and a rubber-like sheath telescopically mounted upon the body portion and peripherally enveloping the same and the female die received free end of the male die, the internal peripheral dimensions of said sheath normally being slightly smaller than the external peripheral dimensions of the body portion when not expanded, said sheath having a sufficient inherent elasticity for self-retention upon the male die body portion and for expanding therewith, the male die support at its junction with the male die having a cross-sectional area appreciably less than that of the male die at that junction, whereby the male die at that junction forms a shoulder, said sheath having its open end positioned upon said shoulder and defined by a slightly reenforced edge, said expansible die being of so-called solid rubber type, said sheath closely conforming to the surface thereof for the protection of the product in all stages of die expansion, said sheath being of a rubber-like material other than that of the so-called solid rubber type and which will not contaminate the interior surface of the pressure moldable product.

7. In a die structure the combination of a male die, a support therefor, and a rubber-like sheath, the male die comprising a body portion supported at one end by the support and the end opposite the supported end being free and of pressure molding type and laterally expansible for molding purposes, the sheath being normally slightly smaller in cross-sectional area than that of the die corresponding area and encompassing the free end of the die and having sufficient inherent elasticity for self-retention upon the die in the normal use thereof, the junction of the die and support providing a shoulder, the sheath terminating at the shoulder and bearing thereon.

LEE M. WILEY.
